EMIL BURHOP, OF GENEVA, SWITZERLAND

EXPLOSIVE ENGINE

Application filed October 15, 1927, Serial No. 226,456, and in Germany December 13, 1926.

The invention is an improvement in explosive engines, particularly intended for automobile vehicles, and of the kind which comprise explosion chambers arranged in pairs. 5 The essential new features of the engine according to this invention are the following ones: firstly, all the intermediary members serving for transmitting the power from the piston or pistons to the driven machine or 10 apparatus are arranged so as to make exclusively reciprocating or swivelling motions, second, each one of the explosions which in the individual chambers of a given pair take place at different times cause all the members 15 to move which are adapted to be operated by the said pair of chambers, thirdly, the effect of the masses of at least the entirety of the members which are operated by the explosion in a given chamber so as to move in one direction is equal to the effect of the masses which in the course of the subsequent explosion in the other chamber will be operated so as to move said members in opposite directions, fourthly, the power transmitted to 20 the driven machine or apparatus is always the same no matter in which one of the chambers of a given pair of chambers the explosion had taken place.

Reference is to be had to the accompanying drawings forming a part of this specification, in which similar characters of reference indicate corresponding parts in all the views.

Both the working examples shown refer to 35 engines in which the two chambers of a given pair of them are arranged in two different cylinders which individually do comprise but a single piston.

Fig. 1 is a diagrammatical view of the 40 essential parts of a two-stroke engine driving a four cylinder oil pump.

Fig. 2 shows another working form in which also a two-stroke engine drives an electric current generator, those parts which 45 generate the current exclusively making reciprocation motions.

Figure 3 is a plan view of Fig. 2.

Figures 4 and 5 are detail views of the atomizing nozzle.

50 Since each one of the cylinders in the par-

ticular two working forms shown comprises but a single chamber the term "cylinder" used for the sake of simplicity throughout the following description would refer to one chamber of a given pair of chambers. 55

In Fig. 1 the members 20 and 20' are the cylinders arranged in pairs, the axis of cylinder 20' constituting a prolongation of the axis of the cylinder 20. The pistons 19 and 19' are carried on a common piston rod 27. 60 By means of the bridges 40 and 40' respectively the pistons 29 and 29' of the oil pumps are rigidly connected with the cylinders 20 and 20' respectively.

The pistons 29 and 29' which are arranged on a given side (to the right or to the left) of the piston rod 27 are rigidly connected with one another by a rod 31. The piston rod 27 carries a middle bridge 40" having about twice as much weight as either of the individual bridges 40 or 40'. The ends of the middle bridge 40" are rigidly connected respectively with double pistons 28 and 28'. Each rod 31 which connects one piston 29 with another piston 29' slides in a longitudinal channel provided in each of the double pistons 28. The middle bridge 40" together with the double pistons 28 and the piston rod 27 and pistons 19, 19' is suspended by means of the rods 30 on the balance 33. The bridge 80 40' with cylinder 20' and the four pump pistons 29 and 29' connected by the rods 31, and the bridge 40 with cylinder 20 is suspended or connected with said balance 33 by means of the rods 32. 85

All the parts adapted to move owing to an explosion in cylinder 20 are, at least in their entirety, equal in weight or effect to the parts moved in an opposite direction by a subsequent explosion in cylinder 20'. 90

The engine shown diagrammatically in Fig. 1 operates as follows:

An explosion in cylinder 20 will cause the up stroke of the piston 19 and piston 19' connected with the former by rod 27. Also the 95 middle bridge 40" carried on rod 27 with the two double pistons 28 of the oil pumps will partake of the upward motion. This same explosion in cylinder 20 has caused a down stroke of the cylinder 20 which by means of 100

bridge 40, pistons 29, rods 31, pistons 29', bridge 40' and rods 32 is suspended on the balance 33, all these parts 40, 29, 31, 29', 40' and 32 partaking of the downward motion of 5 the cylinder 20. It is to be noted that this downward motion is assisted by the simultaneously rising rods 30 connected with the outer ends of the balance 33.

From this it follows that an explosion 10 in the cylinder or chamber 20 will produce the following simultaneous effects:

1. On the one part the up stroke of the pistons 19 and 19', on the other part the down stroke of the cylinders 20 and 20';

15 2. On the one part the up stroke of the middle bridge 40'', on the other part the down stroke of the bridges 40 and 40';

3. On the one part the up stroke of the two double pump pistons 28, on the other part 20 the down stroke of the four single pump pistons 29 and 29';

4. On the one part the up stroke of the piston rod 27 and rods 30, on the other part the down stroke of the two pump piston rods 31 25 and the rods 32.

This evidently means that the motions are perfectly symmetrized or balanced.

If subsequently an explosion takes place in cylinder 20' all the movable parts will 30 move in an opposite direction.

If the masses of the parts which are moved simultaneously in opposite directions are of even weight, then it will not be difficult to expressly provide for a perfect equilibrium.

In the course of the up stroke of the double pump pistons 28 and 28' and the simultaneous down stroke of the pistons 29 and 29' the oil will be drawn in the bottom pair of the 40 oil pumps whilst at the same time it will be expelled from the top pair of the pumps. It is therefore evident that the power taken from the movable systems is perfectly equalized or uniform since the friction losses of 45 both of them are practically equal one to the other.

It is evident that under such circumstances the working of the unit is an extremely uniform, steady, and also a silent one, free from 50 any shocks whatever.

Of course it will be easy in the case of a plurality of pumps to bring about the control of the performance or output by simply cutting out or adding respectively individual 55 pump elements, the pistons of which may besides differ in diameter.

In the working form shown in Fig. 2 the pistons carried by rod 27 are arranged in two oppositely disposed cylinders 20. An 60 inlet is provided in the bottom of the cylinders for the admission during the compression stroke of piston 19 of fresh air into the chamber 10' through the opened valve 12. The latter is a light plate valve which during 65 the working stroke of the piston is auto-

matically closed. 3 is a longitudinal channel giving passage during the working stroke of the piston to a fraction of air which passing through valve 4 may enter the ring chamber 5, communicating by means of the bores 6 and 7 with the atomizing nozzle 14. Since the piston 19 even in its top-most position always leaves a certain small space between it and the inner end of cylinder socket 21 whilst the piston reaches with its outer end 75 quite closely to the compression ring 25, the air is compressed to a higher degree in the ring chamber 5 than in the chamber 10.

The spring compression ring 25 is arranged on the outer piston border on a small projection of the cylinder 20. Openings 9 are provided in the bottom of piston 19 allowing the admission of the air which during the working stroke had been compressed underneath the piston bottom, through the bores

3 of cylinder 20 to the chamber 10, thereby expelling the burnt gases through channels 11 and 12 into the exhaust pipe 13. In the outward end of the cylinder 20 is arranged

the cylinder socket 21 which is provided with

90 a support 22 for the valve. The cylinder 20 itself is allowed to slide in the yoke 23.

The valve cone 14 is held on its seat by the action of spring 15, the strength of

95 which is such as to make sure that by means of a vacuum or lower pressure prevailing in the chamber 10 as compared with the compression in chamber 5 it is slightly raised from its seat and that the compressed air in chamber 5 may be expelled through the bores

6 and 7 and through the said valve opening. The valve disc is provided with small bores

16 and 17 across which the liquid fuel may be drawn in in the very moment in which the

burnt gases are expelled from chamber 10 over the exhaust pipe 13 by means of the

cleaning air admitted through the bores 8, 9. The mixing of the fuel with the air keeps on

100 even after the compression stroke has already begun and therefore the exit of the fuel from the distributing notches 17 is maintained and

105 extends through a comparatively long period of time from which results that the fuel threads may be extremely thin and conse-

110 quently a very fine atomizing or spraying of the liquid fuel is obtained.

The valve 14 will be closed only after the

115 piston 19 has reached again the end of its up stroke that is to say after the explosion had

120 taken place.

When the compressed gas mixture explodes

125 the piston 19 will be forced inwardly into about half the height of the stroke which is

variable in accordance with the degree of the compression.

Two field magnet cylinders 28 are rigidly

130 connected with the piston rod 27. The sup-

port rods 31 which are rigidly connected with

135 the cylinders 20 by means of the bridge 40, carry ring armatures 29. Each one of the

two balances 33 swivelling on the bolts 34 are connected on the one part by means of rod with the magnet cylinder 28 and on the other part by the rod 32 with the bridge 40 which 5 is fixed to the inward end of the cylinder 20 and which also carries the support rods 31 of the ring armatures 29.

Since an explosion of the gas mixture acts in known manner on all the walls surrounding the explosion chamber and since the projection surfaces of the piston bottom and the socket 21 are equal, the latter will together with cylinder 20 be driven outwards whenever the piston is driven inwardly. As the 15 weight of the masses subjected to movements in opposite directions will preferably be made equal it will be understood that an equal acceleration of the masses will be obtained.

20 The cylinder 20 in the portion A of the engine which has been driven outwards owing to the fact that its socket 21 works also like a piston will in the course of a subsequent explosion of the cylinder in portion B of the engine be returned to its former position, and so on.

The balance rods 30, 33 and 32 as well as the bridge 40 serve simply for supporting the unit.

30 As will be seen the magnet cylinder and the armature slide in opposite directions to and fro just like a loom shuttle when the engine is in service, causing the magnet lines of force to be intersected and an electric current to be generated, which in known manner 35 may be utilized in the driving motors of a vehicle and for charging the storage batteries and the like.

The control of the liquid fuel feed may be 40 effected by making the cone of valve 4 by means of rod 39 and disc 38 to close more or less so that more or less air or none at all may be returned from the ring compression chamber 5 to the chamber 10 and by thereby 45 varying the difference of compression existing in chamber 5 on the one part and in chamber 10 on the other part.

In view of the inertia effect of the moving masses it appears advisable to provide that 50 the fuel channel 35 beginning with the opening 18 and ending with the link 36 of the feed pipe which may swing on the bolt 24, is constituting communicating tubes.

The compression of the gas mixture can be 55 given such a value that self ignition will take place which in the case of the engine shown is not only allowable but offers marked advantages. The sparking plugs shown in Fig. 2 may be used when starting.

60 It is also possible to provide for a member sliding on any one of the reciprocating parts which in the case of a failure of the automatic self ignition will operate on an electric contact device when by the inherent inertia it is 65 thrown forward after the piston has reached

its dead point position in a given stroke. This additional ignition device is intended to usefully operate whenever by reason of a sudden overcharge the compression of the gas mixture does not attain the high degree which is required for its self ignition. Of course 70 this kind of inertia ignition device may constitute also the exclusive ignition device provided for a given engine.

Particular attention is to be paid to the 75 perfect equilibrium of the moved masses, no matter which in a given working manner be the design of the particular engine, that is to say, no matter whether in the case of a non-sliding cylinder a single explosion chamber with two pistons, or two explosion chambers with two pistons or if finally in a fixed cylinder with two explosion chambers having but a single piston arranged between them is provided for, and so on.

If in the foregoing the equilibrium of the 80 masses has been spoken of it is of course to be understood that the required symmetrical effect of the masses may be arrived at not only by their equal weight but also, at least in part, 85 by corresponding lever devices.

Whilst in the first working example the engine is shown as driving a multi-cylinder pump and in the second one as driving an electric current generator, it is evident that the engine might be used to operate any machine, device or apparatus whatever, whereby the latter might also make only reciprocating movements or swivelling and even rotating movements.

The number of the pistons operating on a 90 given power consuming device (28, 29) may be chosen at will, and the particular design 95 of the engines may differ from the details shown with regard to the examples described and illustrated. The essential matter is only this that the four characteristical features 100 enumerated in the second paragraph of this specification are realized in a given engine.

Having thus described my invention I 105 claim as new and desire to secure Letters Patent:

1. In an explosive engine having explosion cylinders arranged in pairs and provided with pistons, intermediary members for transmitting power from the pistons to the apparatus to be driven, said members being arranged so as to make exclusively reciprocating or swivelling motion, and means whereby each one of the explosions in a cylinder of a given pair causes all the members 110 controlled by said pair to move.

2. In an explosive engine having explosion cylinders arranged in pairs and provided with pistons, intermediary members for transmitting power from the pistons to the apparatus to be driven, said members being arranged so as to make exclusively reciprocating or swivelling motion, means whereby each one of the explosions in a cylinder of a 115 120 125 130

given pair causes all the members controlled by said pair to move, and means whereby the effect of the masses of the entirety of the members operated by the explosion in a given chamber and movable in one direction will be equal to the effect of the masses operated by the explosion in the other cylinder and movable in an opposite direction.

3. In an explosive engine having explosion cylinders arranged in pairs and provided with pistons, intermediary members for transmitting power from the piston to the apparatus to be driven, said members being arranged so as to make exclusively reciprocating or swivelling motion, means whereby each one of the explosions in a cylinder of a given pair causes all the members controlled by said pair to move, means whereby the effect of the masses of the entirety of the members operated by the explosion in a given cylinder and movable in one direction will be equal to the effect of the masses operated by the explosion in the other cylinder and movable in an opposite direction, and means whereby power transmitted to the driven apparatus will be always the same.

4. In an explosive engine, a balanced pivoted support, a piston carrying unit, and a cylinder carrying unit, one of said units being supported by said balanced support on one side of the pivot and the other unit on the other side of said pivot, said units being of equal weight to adapt them to move correspondingly one in one direction and the other in the opposite direction when an explosion occurs in one of the cylinders.

5. In an explosive engine, a balanced pivoted support, cylinders arranged in pairs and in longitudinal alinement, pistons reciprocable in said cylinders and connected to move in unison, a frame connected to move with said pistons, a connection between said frame and support, another frame connected with and carrying said cylinders, a connection between said cylinder frame and said support, whereby the piston and cylinder frames are balanced, one of said frames being moved in one direction and one in the other when an explosion occurs in one of the cylinders.

In testimony whereof I affix my signature.
EMIL BURHOP.
